UNITED STATES PATENT OFFICE.

DANIEL SHAW WAUGH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,225,898.

Specification of Letters Patent. Patented May 15, 1917.

Application filed February 19, 1915. Serial No. 9,477.

To all whom it may concern:

Be it known that I, DANIEL S. WAUGH, a citizen of the United States, residing at Denver, in the county of Denver and State 5 of Colorado, have invented new and useful Improvements in Rock-Drills, of which the following is a specification.

The present invention relates to rock drills, and in the embodiment disclosed, to 10 that of the hammer piston type.

The primary object of the present invention is to provide novel and effective means for rotating the drill by a separate motor from that which actuates the drill to effect 15 the drilling operation.

One of the primary objects is to provide novel means of a simple character, whereby the drill may be placed against the work before it is thrown into operation, said 20 means also controlling the operation of the actuating motor and the rotating motor in a manner that will permit the latter to operate effectively, while the actuating motor can be throttled down so as to strike a light 25 blow. This, it will be understood, is advantageous when the drill bit has a tendency to stick.

Another and important object is to provide means whereby the motive fluid which 30 actuates the drill rotating motor is independent or separate from that supplied to the drill actuating motor, but the distribution of said motive fluid to the rotating motor, and consequently the operation of the 35 latter, is dependent on the operation of the drill actuating motor.

Another feature of the invention resides in means whereby the drill rotating motor is supplied with motive fluid for a longer period 40 on its working stroke than on its return stroke, thus insuring a proper movement of the drill.

An embodiment of the invention that has been found satisfactory for carrying out 45 these and other objects is disclosed in the accompanying drawings, wherein:

Figure 1 is a longitudinal sectional view through the drill mechanism.

Fig. 2 is a plan view of the same partially 50 in section.

Fig. 3 is a cross sectional view on an enlarged scale and on the line 3—3 of Fig. 1.

Fig. 4 is a detail horizontal sectional view in different planes of the distributing valve

for the drill rotating motor and illustrating the arrangement of the various ports. 55

Fig. 5 is a cross sectional view on an enlarged scale and on the line 5—5 of Fig. 1.

Fig. 6 is a detail perspective view of the ratchet mechanism and chuck sleeve. 60

Fig. 7 is a detail sectional view on the line 7—7 of Fig. 2.

Fig. 8 is a detail perspective view of the distributing valve for the drill rotating motor. 65

Fig. 9 is a diagrammatic view illustrating the arrangement of the ports and passages of the apparatus.

Similar reference numerals designate corresponding parts in all the figures of the 70 drawings.

In the embodiment disclosed, a drill actuating motor of well known type is illustrated, comprising a cylinder member 10 having a front piston chamber 11 of relatively large diameter and a rear piston chamber 12 of relatively small diameter, together with a piston 13 located in said cylinder member and having a front enlarged piston head 14 that operates in the piston 80 chamber 11 and a rear reduced piston head 15 that operates in the rear chamber 12. Secured to the rear end of the drill actuating motor is fluid operated means for holding the drill to its work, the same being of the 85 well known type, and a portion thereof in the form of a cylinder 16 being shown. Secured to the front end of the cylinder member 10 is a head 17, and abutted against said head is a chuck, generally designated by 90 the reference numeral 18.

In said chuck is located a rotatable chuck sleeve 19 having a longitudinal socket 20 therethrough that is angular in cross section and is designed to detachably receive a drill 95 bit of similar cross sectional configuration, as is well understood. This drill bit is arranged to abut against a tappet 21 located in the head 17 and projecting into the path of the hammer piston 13. 100

The chuck sleeve 19 is provided with a central series of peripheral ratchet teeth 22 surrounded by a ring 23 having an upstanding lug or arm 24 that is provided with a rounded enlarged head 25. This arm or lug also has an internal socket 26 in which is slidably mounted a spring-pressed pawl 27, which cooperates with the teeth 22, as 105

will be evident by reference to Figs. 5 and 6. The pawl ring operates in a ratchet chamber 28 formed in the chuck head 18, and said chuck head also carries a drill rotating motor.

The said drill rotating motor, as clearly shown in Figs. 1, 2 and 5, comprises a cylinder member 29 disposed transversely to the drilling apparatus, and containing 10 a reciprocating piston comprising spaced heads 30 and 31 operating in the end portions of the cylinder member 29 and connected by an integral yoke 32 having a socket 33 that receives the head 25 of the 15 ratchet ring 23. It will thus be evident that if the piston 30—31 is reciprocated, the ratchet ring 23 will be oscillated and the chuck sleeve will thus be given a step-by-step rotation. As viewed in Fig. 5, when 20 the piston moves to the left, it is given a working stroke inasmuch as the pawl 27 is then interlocked with the teeth 22 of the chuck sleeve 19, while on its return stroke, 25 said pawl rides over one or more of the said teeth.

Referring now more particularly to Fig. 2, fluid under pressure is supplied to the apparatus from any suitable source to and through a nipple 34 threaded into the larger 30 end of a tapered valve seat 35. In this seat is rotatably mounted a tapered valve 36 having on its projecting smaller end an actuating handle 37. The larger end of the valve 36, or in other words that adjacent to the 35 nipple 34, has a longitudinally disposed recess 38 having ports 39 and 40, the port 40 being of greater width than the port 39, as illustrated in Fig. 7. The port 39 is movable into and out of register with a port 41 which communicates by means of one or 40 more passageways 42 with the means for feeding the drilling apparatus and holding it to its work, while the port 40 is movable into and out of register with a port 43 communicating with a passageway 44 extending longitudinally through the cylinder member 10 and head 17, where it communicates with a central internal groove 45 formed around a distributing valve chamber 46 in the 50 chuck head 18. The valve chamber 46 is provided with other annular internal grooves 47 and 48, and a passageway 49 leads from the groove 47 to one end of the drill rotating cylinder 29. Another passageway 50 leads from the other groove 48 to the opposite end of said cylinder. In addition an exhaust port 51 leads from one end of the valve chamber 46 into the cylinder 29 between piston heads 30 and 31 and 55 is thus in communication with the ratchet chamber 28. From this ratchet chamber an exhaust passageway 52 leads rearwardly through the head 17 and opens into the outer air.

60 Operating in the chamber 46 is a differen-

tial distributing valve having heads 53 and 54 at its ends, the head 53 being of less diameter than the head 54, and forming between them an annular groove 55 that is in constant communication with the supply 70 groove 45. It thus will be evident that the inner end of the head 54 has a pressure surface 56 which is of greater area than the inner surface 57 of the head 53, so that the normal tendency of the valve is to be in the 75 position illustrated in Fig. 4. It is, however, provided on its larger end with a pressure surface 58, the utility of which is herein-after described. Said valve furthermore has a central exhaust passage 59 that is in 80 constant communication with the port 51, and branches 60 lead from this exhaust passage to the periphery of the larger head 54.

Referring now to Figs. 1 and 2, it will be 85 noted that the throttle valve 36 is also provided with an angular port 61 extending transversely therethrough, being separate from the recess 38. One end of this port is movable into and out of register with a port 90 62 that communicates with the passageway 42 that is connected with the feed means 16, such communication being established by the annular channel 42^a while the opposite end of said port 61 is movable into and out 95 of register with a port 64 communicating with the rear portion of the piston chamber 12 of the drill actuating motor. A passageway 65 leads from said rear portion of the chamber 12 and is provided with two 100 ports, one 66 which opens into the front end of the larger piston chamber 11, while the other 67 passes through the head 17 and opens into the end of the distributing valve chamber 46 in which the larger head 54 105 operates. It will be noted by reference to Fig. 1 that the inlet end of the passageway 65 is covered and uncovered by the head 15 of the drill actuating motor piston 13.

The operation of the apparatus is substantially as follows: The throttle valve 36 may be turned so that all its ports are out of communication with the ports with which they can register, in which case, it will be evident that the motive fluid is entirely shut off 110 from the apparatus. Having set the said apparatus in position to work, the said throttle valve is first turned to bring the ports 39 and 41 into partial register and this can be done without bringing any of 115 the other ports into communication. As a result, it will be evident that motive fluid will be admitted to the feeding means, thereby moving the drill actuating motor to its work, but that said drill actuating motor 120 and the drill rotating motor will still be inactive. If now the throttle valve 36 is turned slightly farther, the ports 40 and 43 will be brought into communication, and the 125 fluid will thus flow through the passageway 120

44 to the central groove 45 of the distributing valve chamber 46. It will here act upon the pressure surface 56 of the valve and move the same to the left, thereby opening communication between the groove 45 and the groove 48, and permitting the fluid to flow through the passage 50 into one end of the cylinder member 29, causing the piston 30-31 to have a working stroke. At the same time that the motive fluid is thus admitted to the drill rotating motor, the ports 62, 61 and 64 will be brought into register, and as a result, motive fluid will pass from the annular channel 42 through the passageway 63, the ports 62, 61 and 64, into the drill actuating motor. As a consequence the hammer piston 13 will be reciprocated. While the said piston 13 is in its rearmost position the distributing valve will be in the position illustrated in Figs. 1 and 4, but when the piston 13 is in its advanced position, its head 15 will uncover the passage 65, thereby admitting motive fluid thereinto and through the ports 66 and 67. The motive fluid which enters the front end of the piston chamber 11 in advance of the piston head 14, will drive the piston 13 rearwardly, and at the same time that which passes through the port 67, will operate on the pressure surface 58. This surface being of greater area than the surface 56, the valve will be moved to the right. As a result, the grooves 45 and 47 will be brought into communication with the groove 55 of said valve, and motive fluid will flow through the passageway 49, so as to cause the piston 30-31 to move rearwardly or on its return stroke. As soon, however, as the hammer piston 13 has moved rearwardly a sufficient distance to cover the ports 65 and open an exhaust port indicated in dotted lines at 65^a, the motive fluid in the passageway 65 will exhaust through said port 65^a, thereby relieving the pressure against the surface 58 of the distributing valve and permitting the pressure against the surface 56 to act and again move the valve to the left. In the operation of said valve, it will be noted that the exhaust ports 60 thereof are intermittently brought into communication with the groove 48, so that the motive fluid behind the piston head 30 can exhaust through the passage 50, the ports 60, the passage 59, port 51, ratchet chamber 28 and passageway 52. When the valve is in the position shown in Figs. 1 and 4, the motive fluid will then exhaust from behind the piston head 31, through the passageway 49, groove 47, port 51 into the ratchet chamber 28, and thence through the passageway 52.

In this operation, it will be noted that the length of time that the motive fluid is permitted to act against the end of the distributing valve by the piston 13, is relatively short, as compared to the length of

time that the valve is held in its left hand position by the motive fluid operating against the pressure surface 56, so that the motive fluid acts upon the piston of the drill rotating motor for a greater length of time 70 during its working stroke than it does during its return stroke. This is obviously a decided advantage. It will also be observed that in this apparatus the motive fluid which actuates the drill rotating motor is not that 75 employed for operating the piston of the drill actuating motor, but that the operation of the distributing valve for the drill rotating motor is dependent on the operation of the drill actuating motor. With this relation of parts disclosed, also, it will be seen 80 that the actuating motor can be throttled down so that it strikes a very light blow, while the rotating motor can be maintained in full operation. Thus, if there is a tendency of the drill becoming stuck, it can be continuously tapped, and at the same time effectively rotated.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new and desire to secure by Letters Patent, is:—

1. In apparatus of the character set forth, the combination with a drill actuating motor, of a drill rotating motor, means for supplying motive fluid to the drill rotating motor, a distributing valve for said motive fluid, and means controlled by the actuating motor for delivering a charge of motive fluid partly against the distributing valve and partly and simultaneously to the motor to 105 move both.

2. In apparatus of the character set forth, the combination with a drill actuating motor including a cylinder member and a piston operating therein, of a drill rotating 115 motor, means for supplying motive fluid to the rotating motor, a distributing valve controlling said supply, and a passageway for delivering fluid against the piston and valve to move them, said passageway being controlled by the actuating motor piston on its movement.

3. In apparatus of the character set forth, the combination with a drill actuating motor including a cylinder member and a piston operating therein, of a drill rotating 125 motor, means for supplying motive fluid to the rotating motor independently of that supplied to the drill actuating motor piston, a distributing valve controlling said supply, 130

and a passageway for delivering fluid against the actuating piston and valve to move both, said passageway being controlled by the actuating motor piston on its movement.

4. In apparatus of the character set forth, the combination with a drill actuating motor, of a drill rotating motor, means for delivering motive fluid to the latter, a differential distributing valve for the motive fluid delivered to the rotating motor, said valve having a pressure surface operated on by said motive fluid, to move the valve in one direction and having an opposed pressure surface, and means controlled by the actuating motor for independently delivering a charge of motive fluid partly to said motor to operate it and partly and simultaneously against said opposite pressure surface. 70

5. In apparatus of the character set forth, the combination with a drill actuating motor, of a drill rotating motor, means for delivering motive fluid to the latter, including a distributing valve chamber, spaced passages leading therefrom to the rotating motor, and a supply passage leading to the intermediate portion of the chamber, a differential distributing valve in said chamber having a pressure surface against which the supply constantly operates and an opposing end surface of greater area, and means controlled by the actuating motor for delivering motive fluid intermittently against said end surface, to move said valve against said constant pressure. 80

6. In apparatus of the character set forth, the combination with a drill actuating motor, including a cylinder member and a piston operating therein, of a drill rotating motor, a distributing valve for the rotating motor, and means for intermittently and simultaneously supplying a charge of motive fluid partly to the actuating motor piston and partly to the distributing valve for simultaneously moving both in one direction. 90

7. In apparatus of the character set forth, the combination with a drill actuating motor, including a cylinder member and a piston operating therein, of a drill rotating motor, a distributing valve for the rotating motor, and means controlled by the actuating motor piston for intermittently and simultaneously supplying a charge of motive fluid partly to the actuating motor piston and partly to the distributing valve for simultaneously moving both in one direction. 100

8. In apparatus of the character set forth, the combination with a drill actuating motor including a cylinder member and a piston operating therein and having a working and return stroke, of a drill rotating motor, a distributing valve for the rotating motor, 110

9. In apparatus of the character set forth, the combination with a drill actuating motor, including a cylinder member and a piston operating therein and having a working and a return stroke, of a drill rotating motor, means for supplying motive fluid to the drill rotating motor independent of that supplied to the actuating motor piston, a distributing valve for the rotating motor having a pressure surface constantly acted on by the motive fluid supplied thereto and having an opposing surface of greater area, and means controlled by the actuating motor piston for simultaneously delivering motive fluid against the same and against said larger pressure surface of the distributing valve. 120

10. In apparatus of the character set forth, the combination with a drill actuating motor including a cylinder member and a piston operating therein, of a drill rotating motor, means for supplying motive fluid to the drill rotating motor including a valve chamber, spaced passageways leading therefrom to the rotating motor and a supply passage communicating with said valve chamber, a distributing valve in the chamber having a back and forth movement and provided with a pressure surface against which the motive fluid constantly acts, and an opposing pressure surface of greater area, means for supplying motive fluid to the drill actuating motor, including a passageway controlled by the piston thereof for delivering motive fluid to cause the return stroke of said piston, and a port communicating with said passageway and delivering against the said opposing surface of the distributing valve. 130

11. In apparatus of the character set forth, the combination with a drill actuating motor, of a drill rotating motor including a piston having a working and a return stroke, and automatic means for supplying motive fluid to and exhausting it from the rotating motor both on its working and return strokes and maintaining the fluid supply for a longer period on its working stroke than on its return stroke. 140

12. In apparatus of the character set forth, the combination with a drill actuating motor, of a drill rotating motor including a piston having a working and a return stroke, and means controlled by the actuating motor for automatically supplying motive fluid to and exhausting it from the ro- 150

- tating motor both on its working and return strokes and maintaining the fluid supply for a longer period on its working stroke than on its return stroke.
- 5 13. In apparatus of the character set forth, the combination with a drill actuating motor including a cylinder member and a piston operating therein, of a drill rotating motor including a cylinder member and 10 a piston operating therein, said piston having a working and a return stroke, means for supplying motive fluid to the rotating motor, a distributing valve for directing the fluid to the rotating motor to alternately 15 cause its working and return strokes, and means for holding the valve in its working stroke position for a longer period than in its return stroke position.
14. In apparatus of the character set 20 forth, the combination with a drill actuating motor including a cylinder member and a piston operating therein, of a drill rotating motor including a cylinder member and a piston operating therein, said piston having 25 a working and a return stroke, means for supplying motive fluid to the rotating motor, a distributing valve for directing the fluid to the rotating motor to alternately cause its working and return strokes, and 30 means controlled by the actuating motor piston for holding the valve in its working stroke position for a longer period than in its return stroke position.
15. In apparatus of the character set
- forth, the combination with a drill actuating motor and a drill rotating motor, of a chuck having a ratchet chamber, a chuck sleeve, and ratchet mechanism in said chamber for effecting a step by step rotation of the chuck, said ratchet mechanism being 35 actuated by the rotating motor, means for supplying motive fluid to the rotating motor, a distributing valve for said motive fluid supply, and exhaust means for said rotating motor controlled by said distributing 40 valve, said exhaust means including a port opening into the ratchet chamber and a port leading therefrom to the open air.
16. In apparatus of the character set 45 forth, the combination with a drill actuating motor, including a cylinder member and a piston therein, of a drill rotating motor, means for supplying motive fluid to the rotating motor, means for distributing such supply, and means for supplying successive 50 charges of motive fluid to the motor, dividing each charge and directing a portion of said charge to the distributing means to operate the same and simultaneously a portion to the actuating piston for operating it. 55

In testimony whereof I have hereunto set my hand in presence of two subscribing witnesses.
